UNITED STATES PATENT OFFICE.

JOHN WITTEMAN, OF MILWAUKEE, WISCONSIN.

DETACHABLE SHADE-HOLDING BRACKET.

Application filed February 9, 1920. Serial No. 357,470.

To all whom it may concern:

Be it known that I, JOHN WITTEMAN, a citizen of the United States, and a resident of the city of Milwaukee, county of Milwaukee, and State of Wisconsin, have invented a new and Improved Detachable Shade-Holding Bracket; and I do declare the following to be a full, clear, and exact description thereof, such as will enable persons skilled in the art to which the invention pertains, to make and use the same, reference being had to the accompanying drawings for a disclosure of one construction in which the invention has been embodied.

My invention relates to brackets for supporting the rollers of window shades.

The invention resides in a bracket designed to be attached to the upper sliding sash of a window, in such position that the upper sash with its shade supporting attachments may be lowered without disturbing the shade attachments, so as to admit ventilating currents of air to pass through the open space above the top of the lowered sash, and thus secure a better hygienic condition in the room from which the window opens.

By reason of the fact that the shade roller is supported by and is moved with the sash, the shade may be drawn and privacy of the room be preserved. Ordinarily, this is a result which cannot be attained without liability of damage to the shade, as it is quite usual to support the shade roller in brackets which are fixed to the front or to the sides of the window casing, and when drawn, the shade is subject to agitation by the ventilating currents of air, with consequent damage to the shade, the latter sometimes being torn from its engagement with the shade roller by violent gusts of wind, and the privacy of the room entirely destroyed until the matter can be remedied.

Again, the desire to protect the shade from damage under such conditions necessitates the shade being fully raised and wound upon the roller, and this again creates that undesirable publicity which the proper use of the shade is intended to obviate.

My invention embodies a flat stirrup or loop designed to be attached to the stiles of the upper sash, and to lie in such proximity thereto that it will not interfere with the raising or lowering of either sash for the purpose of cleaning the window panes.

The peculiar form of bracket which I use for supporting the shade roller is easily connected with the stirrup or loop in a manner to firmly support the shade roller when the latter has been placed in position, and is detachable from its connection with the stirrup or loop with equal facility, whenever it may be desirable to remove the shade and its supporting brackets for any purpose.

The stirrup or loop when secured to the stiles of the sash as before referred to, provides an opening or space into which an angularly formed foot on the shade roller supporting bracket may be entered and retained securely against the possibility of accidental displacement. The journal at one end of the shade roller, and the shaft at the other end, to which the spring for rotating the shade roller is attached, are received in bearings formed in the brackets, and when in position the shade roller acts to perfect the engagement of the foot on each bracket frictionally with its respective stirrup or loop, by exerting a lateral pressure upon the brackets, but while the pressure thus exerted contributes to the effective locking of the parts in their relative positions, such pressure does not in any degree retard the free rotation of the roller when it is desired to raise or lower the shade.

Each of the brackets is provided with a widened stop formed as a part thereof and designed to contact with the meeting rail of the lower sash, and so prevent damage to the latter, should the lower sash be raised so high as to contact with the brackets.

In the drawings which form part of this specification,

Figure 1 is a view in elevation showing an ordinary window frame, looking from the interior of the room, and showing the manner in which my improved detachable shade holding bracket may be used.

Fig. 2 is an enlarged plan view, showing the top rails of both sashes, and my improved bracket in position at one side of the window casing, the latter being shown in section, and showing also the relative arrangement of the stirrup or loop and the bracket at the other end of the shade roller.

Fig. 3 is a view in elevation of the stirrup or loop.

Fig. 4 is a view in elevation of the bracket.

The general arrangement of the parts is

shown in Fig. 1 of the drawings. In this view, the upper sash to which the attachments are applied, is shown as partly lowered so as to provide a ventilating opening, 5 through which currents of air, no matter how strong, may pass without vibration of the fabric of which the shade is composed. In this view, the shade is shown as but partially drawn, but it is obvious that the 10 shade may be completely drawn so as to secure privacy in a room, and still maintain the provisions for ventilation.

In Fig. 2 the bead A and the parting strip B, set in grooves in the casing C of 15 the window frame, serve to guide the upper sash D, and between the strip B and the stop E, fixed to the casing, the lower sash F will be guided, all as usual in similar building constructions. The sashes are thickened 20 at their meeting rails, so that when the chamfered or beveled portions d and f of the rails are brought together, the space in the line of the parting strips will be closed.

To each of the stiles of the upper sash D, 25 and at or near the top thereof, I attach the stirrup or loop H, shown in Fig. 3, and in cross section at the right in Fig. 2. In the latter view, the central or engaging portion of the stirrup or loop is offset and inclined 30 as at h, with respect to the plane in which the stirrup or loop lies when attached to the sash, the angle of such inclination diverging from the sash toward the middle line thereof, whereby there is formed a pocket 35 having a restricted opening adjacent the vertical edges of the sash. Each stirrup or loop is set a measured distance from the edge of the sash so as to provide a clearance for a purpose to be presently described. As 40 shown, the extremities of the stirrup or loop are provided with perforations through which are passed the means for securing the part to the sash.

A bracket I is provided with a foot i, 45 formed integrally therewith, and bent to an angle which is slightly acute, which foot will be of a length not exceeding the width of the clearance hereinbefore referred to. The foot of the bracket is slipped laterally 50 into the restricted opening and seated in the pocket, before described, and is thus held in position to receive and support the shade roller. In the matter of length, the brackets will extend sufficiently beyond the vertical plane in which the lower sash may be 55 moved, to permit the said lower sash to be raised without contact with the shade which depends from the roller journaled in the ends of the brackets. The relative position 60 of the roller is indicated in Fig. 2. One of the brackets will be provided with a circular bore for the reception of the journal or pin in one end of the shade roller. Such bore is indicated by full lines in Fig. 4. 65 The other bracket of the pair will be pro-

vided with a slot or angular opening for the reception of the end of the spring shaft at the other end of the shade roller, whereby the said shaft will be held against rotation, during the rotation of the shade roller 70 under the pressure exerted by the spring connecting the shaft and roller, as is well known. The approximate dimensions of such slot are indicated by dotted lines, Fig.

4. A widened stop i', formed integrally 75 with the bracket at the lower edge thereof, and standing at a right angle thereto, is adapted to project over the lower sash so as to contact with the meeting rail of the latter when such sash is raised, and thus 80 prevent damage to such rail by reason of the broadened bearing surface thus provided.

In assembling the parts of the invention, the foot on the bracket is inserted in the stirrup or loop, as previously described, and the 85 pintles of the shade roller are inserted in the respective openings in the brackets, by springing such brackets apart in a slight degree, and as indicated by the dotted lines in Fig. 2. The inherent resiliency of the construction is such that the frictional engagement between the stirrup or loop and the foot of the bracket will hold the parts in their assembled positions and against accidental displacement, and the shade roller, 90 acting as a distance piece between the brackets will serve to make the locking engagement of the parts more effective.

From what has been described as to the manner of assembling the parts, it is obvious 100 that disassembling or detachment of the parts may be effected with equal facility. When detached, both sash may be moved the full length of the window frame, without interference by the stirrups or loops, which latter lie entirely beyond the plane of movement of the bevelled or chamfered portion of the meeting rail of the lower sash, and consequently no damage to such sash will be caused by the but slightly projecting stirrups or loops when the sash are shifted from top to bottom, as will be desirable in cleaning the window panes, or for other purposes.

By reason of the angular engagement of the foot of the bracket with a stirrup or loop, the bracket cannot be released from such engagement until after the bracket has been moved or turned on its heel i', so as to bring the foot into parallelism with the plane of the sash. It will be clear that when the brackets are separated by the placing of the shade roller in position, there can be no such turning movement of the bracket, and that any bodily outward movement thereof is prevented.

My invention possesses several very convenient features, and may be produced, by reason of the simplicity of its construction, at a very low cost.

Having thus described my invention, what 130

I claim and desire to secure by Letters Patent of the United States, is:

1. A window shade fixture comprising a bracket holding stirrup or loop for attachment to a window sash, such stirrup or loop having the bracket sustaining part thereof disposed at an angle which is inclined with respect to the plane of the sash, and a shade roller supporting bracket provided with a correspondingly forward angularly extending foot adapted for engagement with the stirrup or loop, whereby when engagement of the angular faces of the foot of the bracket and the sustaining stirrup is effected, the bracket is held against displacement.
2. A window shade supporting fixture comprising a stirrup or loop for attachment to the front side of a window sash, such stirrup or loop having a bracket engaging portion offset from the plane of the sash, and a roller-supporting bracket provided with an angularly extending foot adapted to be loosely inserted in the engaging portion of the stirrup or loop, a like fixture at the other side of the sash, and a shade roller extending between and supported by the said brackets and adapted to spread them apart to effect locking engagement of the feet on the brackets with the stirrups.
3. A detachable window shade fixture comprising a stirrup or loop for attachment to a window sash, such stirrup or loop hav-

ing a bracket-sustaining portion offset and inclined from the plane of the sash, a roller-supporting bracket having an inclined foot 35 adapted to be loosely inserted in the sustaining portion of the stirrup or loop, and means for moving the bracket to effect a locking engagement of the said inclined parts to prevent accidental displacement of 40 the bracket while a shade is in position.

4. A shade holding fixture for windows with sliding sash, comprising a stirrup or loop for attachment to the front side of the upper sash, and adapted to lie wholly outside of the plane of movement of the lower sash, a roller-supporting bracket having an angularly extending foot thereon for frictionally engaging the stirrup or loop to retain the bracket in position, and having a 50 wide bearing stop on one edge thereof to arrest relative movement of the sash past each other, the bracket being slidably demountable from the stirrup to permit the sash to be moved the full length of the window 55 frame, without contact with the said stirrup.

In testimony whereof, I have signed my name at Milwaukee, this 7th day of February, 1920.

JOHN WITTEMANN.
